CATALYTIC REACTION OF ALKALI METAL HYDRIDE AND BORON TRIHALIDE

Everett H. Pryde, Kenmore, N. Y., assignor to
E. I. du Pont de Nemours and Company, Wil-
mington, Del., a corporation of Delaware

Application June 24, 1952, Serial No. 295,310

17 Claims. (Cl. 23—14)

1

This invention relates to the borohydrides of alkali metals and more particularly to sodium borohydride.

In the patent application Serial No. 295,266 of Hansley and Pryde, filed of even date herewith, there is disclosed a method for producing sodium borohydride by means of the reaction:

While the reaction shown had not been carried out previously, the yield obtained was, at best, only about 51%. I have discovered that a yield much higher than 51% can be obtained if a catalyst be employed during the course of the reaction shown. A primary object of the invention is therefore development of an improved process for making alkali borohydrides, useful compounds which may serve as reducing agents.

It has been found that if an alkoxide, such as sodium methoxide, be added to powdered sodium hydride and boron trifluoride is passed over the resulting mixture a yield of up to about 88% sodium borohydride may be obtained in contrast to the 51% reported. The temperature for the reaction should be controlled within the range 150°—400° C. and preferably held between about 250° and 300 C. In the preferred embodiment of the invention approximately stoichiometric quantities of gaseous boron trifluoride at atmospheric pressure are led over an agitated mass of comminuted sodium hydride and sodium methoxide, agitation being carried out in a closed reactor in a blanket of inert gas substantially excluding moisture and air. For best results a heel of material from a previous run is mixed with the sodium hydride currently utilized to improve yields and help prevent the caking of the solids. The crude borohydride mixture thus prepared can be utilized directly as a reducing agent or purified by extraction with isopropyl amine and subsequent solution in absolute ethyl alcohol.

Of especial importance to the instant process is agitation of the reactants. This expedient reduces undesirable caking of the solids and allows the reaction to proceed further towards completion than it otherwise would. While any conventional agitation means may be employed, a stainless steel ball mill reactor has been found particularly advantageous. A mill convenient for the purposes of this invention is substantially that described in "Industrial and Engineering Chemistry," 43, 1759—1766 (1951), particularly at page 1764, and is shown in the figure, which represents a view, partly in elevation and partly in section, of the apparatus utilized.

2

In the figure a stainless steel reactor 10, containing steel balls 11, is shown supported by bolts 12 and shaft 13, the shaft being rotatably connected to air motor 14 through appropriate gearing. Careful machining at flanges 16 permits a gas tight fit to be made between reactor 10 and neck 17. Neck 17, like the reactor formed of stainless steel, is supported at roller bearing 18 by stand 19 and terminates in spherical brass joint 20. Joint 20 provides rotatable contact between glass adaptor 21 and neck 17. Tension springs 22 and 23 hold the adaptor to stand 19 with any desired resilient force. An outlet arm 25 forming a gaseous exit for the entire system is integral with adaptor 21. The free end of adaptor 21 is closed by stopper 26 through which is inserted thermocouple well 27 and inlet tube 28. Air motor 14 is held at pivot 29 to stand 30 which in turn is rigidly fastened to base-plate 31 at a predetermined distance from stand 19. Furnace 32, supported on base-plate 31, is constructed around the reactor 10, holes being left to admit passage therethrough of shaft 13 and neck 17. Furnace 32 may be made of any convenient heat resistant material. If constructed of discrete units such as magnesia fire-brick, the furnace may however be easily assembled or dismantled. Heat is supplied to reactor 10 by any convenient source such as a small flame (not shown) playing into the furnace.

30 The operation of the apparatus is believed evident from the description. Reactor 10 was charged with balls 11 and solid hydride and nitrogen led in through inlet tube 28 to blanket the entire system and ensure exclusion of air and moisture. A rotameter (not shown) was inserted after outlet arm 25 to measure gas flow. After the air had been replaced by nitrogen, milling was commenced, the reactor being rotated by the motor 4, and BF_3 gas fed through inlet tube 28. When the absorption of BF_3 was considered complete the glass adaptor 21 was disconnected at joint 20, the furnace 32 disassembled and the reaction product removed from the reactor. To assist in the product removal the mill may be dropped downward by means of pivot 29.

Details of the instant process may be more easily understood from the specific examples following. Example 1 is included merely for ease in contrasting procedure which does not use an alkoxide catalyst with procedure utilizing such a material.

Example 1

The stainless steel reactor was charged with $\frac{3}{4}$ " steel balls, 234 grams of product from a pre-

3

vious run, the product analyzing 14.0% sodium hydride and 11.9% sodium borohydride, and 110 grams (4.58 gram moles) of free sodium hydride. The reactor was then mounted in position, evacuated and filled with dry nitrogen at atmospheric pressure. The ball mill was started and heating begun. When the temperature had reached 160° C. boron trifluoride gas was passed in at atmospheric pressure and a rate of about 500 cc. per minute. Absorption of boron trifluoride gas gradually decreased until after about an hour of heating there was a sudden rise in temperature, the absorption then remaining steady at about 500 cc. per minute for another hour. During this period the temperature varied from 230° C. to 300° C. After two hours the rate of absorption again gradually decreased and finally practically ceased. The flow of trifluoride was then stopped and cooling begun. A total of 0.21 mole BF_3 was absorbed for each mole of NaH present the theoretical or stoichiometrical figure being 0.25. The product was analyzed and found to contain 8% sodium hydride and 10% sodium borohydride, the yield of the latter being 51%. It may be noted that, despite the precautions taken, there was some packing of the final product

Example 2

(a) A run was made to determine the catalytic efficiency of sodium methoxide (NaOCH_3) on the reaction between sodium hydride and boron trifluoride. The procedure followed was generally that of the previous example except for the addition of the catalyst. Into the reactor were charged 5.78 moles (138.9 grams) of commercial grade sodium hydride, 102 grams of heel from a previous reaction in which no methoxide had been utilized and 12.8 grams of commercial sodium methoxide. The heel contained 0.34 mole of NaH and 0.27 mole of NaBH_4 . The methoxide added was equivalent to 0.237 gram mole or 0.039 mole for each mole of sodium hydride present. After the mixed solids had been milled in a nitrogen atmosphere for about an hour, heat was applied to the furnace and the temperature in the reactor raised to 240°. The flow of boron trifluoride at atmospheric pressure was then begun and continued for about 2 hours, the temperature varying during the reaction period between 238°-270° C. The product obtained was found to be somewhat packed but was nevertheless utilized as a heel in a further reaction.

(b) To the product of the previous reaction were added an increment of 7.92 moles or 190.0 grams of sodium hydride and 28 grams of sodium methoxide, the methoxide increment representing 0.518 gram mole or 0.065 mole for each additional mole of sodium hydride. The ball mill was started and the furnace heated. When the reactor temperature had reached 225° C. the boron trifluoride stream was again admitted. After about an hour a sudden surge in temperature necessitated stopping the trifluoride flow. Hydrogen was passed through the system for a short time to cool the reactor. When the temperature had again reached 234° C. boron trifluoride was passed through the apparatus for about 1½ hours more, a total of about 2½ hours reaction time being required for reacting the second NaH increment.

The product obtained upon cooling the reactor was analyzed, showing a weight percentage of 12.6% sodium hydride and 11.3% sodium boro-

4

hydride, 0.22 mole of BF_3 being absorbed for each mole of NaH initially present. The borohydride yield represented a 53.6% conversion of the hydride utilized. This value is slightly higher than any obtained in the absence of methoxide catalyst and in addition the product showed no signs of caking, being entirely free-flowing.

An Edwards Analyzer, described in "The Analyst," 71, 521 (1946), was utilized throughout these experiments. This instrument, standard for hydride analysis, determines the amount of hydrogen evolved by means of pressure changes. Methyl Cellosolve, which reacts with sodium hydride but not with hydride, was first added to the sample under inspection. The amount of hydrogen found was a measure of NaH present in the sample. Methyl Cellosolve acidified by small amounts of sulfuric acid was next added to the sample. The hydrogen evolved from the second Cellosolve addition was a measure of NaBH_4 present. The method was tested against known samples.

Example 3

Another run was made using 7.54 moles of sodium hydride (181 grams), 150.7 grams of the product shown in Example 2 and 58.9 grams of sodium methoxide. The percentage of methoxide catalyst was increased over that previously used to 58.9 grams, representing 1.09 gram moles or 0.13 mole for each mole of NaH . Boron trifluoride was passed through the reactor for about 3½ hours at a temperature ranging from 250° C. to 310° C. Analysis of the product showed an 88.6% conversion of sodium hydride to sodium borohydride, 0.25 mole of BF_3 being absorbed for each mole of NaH in the original solids.

Example 4

The procedure of Example 3 was repeated with 120 grams of the product of that example, 173 grams (7.2 gram moles) of sodium hydride and 51 grams (0.94 gram mole) of powdered sodium methoxide. The ratio of methoxide to hydride was 0.13 as before. Boron trifluoride was introduced at a temperature of 240°-300° C. over a period of four hours. The product showed a yield of 87.8% borohydride based on the total sodium hydride used and was free-flowing.

Example 5

The procedure of the previous examples was repeated except that the ratio of NaOCH_3 to NaH was reduced to 0.1:1. 82 grams of a heel containing 1.8% NaH , 14.2% NaBH_4 and 9.3% NaOCH_3 , were mixed with 132 grams (5.5 moles) NaH and 22.1 grams (0.41 mole) NaOCH_3 . BF_3 was added during a period of 2½ hours in which the temperature varied from 232° to 288° C. The product showed 12.21% NaBH_4 , a yield of 86.4%, and substantially no NaH .

Example 6

(a) The procedure of Example 5 was repeated except that the previously prepared heel was omitted. A charge of 210 grams (8.75 gram moles) of NaH and 78.7 grams (1.46 gram moles) of NaOCH_3 were placed in the reactor and milled, the mole ratio of methoxide to hydride being calculated at 0.17. Boron trifluoride was admitted for about 3 hours to the agitated mixture at a temperature of 240°-290° C. and gave a product showing a yield of only 67.6%.

(b) The trifluoride gas was led over the solids for about 2½ hours more at a temperature of

240°-264° C. The yield was increased to 77.8% by this treatment but the product was partially packed into a hard cake.

The results of the experiments given in the examples are summarized in Table I.

TABLE I—PRODUCTION OF NaBH_4

Example	NaH, Moles	Heel, Gram	NaOCH ₃ , moles/mole NaH	Temp., °C. Min.-Max. (Mean)	Reaction Time, Hours	Yield (Percent Borohy- dride)
1-----	4.58	234	0	150-307 (250)	2½	51
2a-----	5.78	102	0.039	238-270 (250)	2	-----
2b-----	7.92	(1)	0.065	240-300 (260)	2½	53.6
3-----	7.54	150	0.13	250-310 (270)	3½	88.6
4-----	7.20	120	0.13	240-300 (270)	4	87.8
5-----	5.50	82	0.10	232-288	2½	86.4
6a-----	8.75	0	0.17	240-290	3	67.6
6b-----	(2)	(2)	(2)	240-284	2½	77.8

¹ Cont. from 2a.

² Cont. from 6a.

It will be seen that the sodium methoxide catalyst markedly increased the yield of borohydride obtained. Quantities of as low as 0.039 mole of the catalyst to each mole of sodium hydride employed appeared to have some effect but best results were found when about 0.1 mole of methoxide was used for each mole of the hydride. A mole ratio of 0.17:1 still gave results not quite as good as those obtained with a mole ratio of about 0.13:1 but still above those obtained in the absence of a catalyst. A ratio of up to about 0.20:1 would therefore seem preferred although higher values can be used with diminishing effect. The alkoxide does not affect the temperature requirements of the reaction, the 150°-400° C. range being operative with about 250°-300° C. being preferred.

The effect of the heel may be seen by contrasting the results of Example 6 with those of Examples 3 or 4. Omission of the heel not only decreased the yield but resulted in a packed product. Accordingly, while a heel from a previous reaction is not absolutely essential, it is desirable. The heel should be added to the hydride in an amount equal in weight to between about 1.0 to 2.5 times that of the latter. Calculations must of course take into account the sodium hydride added with the heel. Other inert materials may be substituted for the reaction product of a previous run but such a product is preferred.

One effect of the added heel is to serve as a mere diluent of the reagents, thereby slowing down the reaction. The steel balls in the ball mill may also serve somewhat the same purpose. The balls may behave in addition as heat exchange media, rapidly lowering an excess temperature occurring at any particular spot. Heat exchange characteristics may also explain the efficacy of steel as a constructional material for the closed reaction chamber. While various methods of heating this chamber may be employed, as for example resistance wiring, a flame playing into a furnace and never touching the reactor itself was found of particular value.

The crude reaction product shown above is mixed with NaF, NaH, NaOCH₃ and side products. It may be employed as a reducing agent in the original mixture or it may be concentrated and purified as desired. A product containing 10-14% borohydride was treated with isopropyl amine in a Soxhlet extractor to give a material containing 51% borohydride. The amine was

evaporated and the borohydride dissolved in absolute ethyl alcohol and reprecipitated with petroleum ether. The final product was sodium borohydride of 90% purity. Further purification may be carried out at discretion.

Various modifications within the scope of this invention will be evident to those skilled in the chemical arts. Hydrogen and nitrogen have, for example, been shown as coolant or non-reactive atmospheres. Other inert gases may be utilized instead of these two, available substitutes being helium, neon and argon. Furthermore the sodium hydride and methoxide used may be either freshly prepared or commercially obtained without affecting the results of the process. Still furthermore, the reactants themselves may be varied slightly. LiH, KH and other alkali metal hydrides may be substituted for NaH, producing the respective metallic borohydrides. In addition, other boron halides such as BCl_3 , BBr_3 and mixed halides may be substituted for the BF_3 . The quantity of boron halide passed over the solids is not strictly critical since, under the given conditions, the reaction substantially stops of its own accord when about one-quarter mole of BF_3 has been absorbed for each mole of NaH present.

The invention is also not to be understood as restricted to the catalyst exemplified. Other alkoxides may be used instead of the methoxide such as NaOC_2H_5 , NaOC_3H_7 and other simple alkaline alcohohlates. In addition the phenates, such as NaOC_6H_5 , are available. The more alkaline the catalyst, however, the more desirable it will generally be found, acids tending to promote the decomposition of the borohydride. If the sodium hydride is to be replaced by the hydride of another alkali metal, the catalyst should be an alkoxide of the same metal. Thus with KH it would be desirable to use KOCH_3 , KOC_6H_5 or another potassium compound. In general the formula of the catalyst may be written as MOR where M stands for an alkali metal ion and R an aliphatic radical of fairly low molecular weight, that is, with a carbon chain up to about five or six atoms long, or a simple aryl radical of the phenyl type.

The quantity of alkoxide required to serve as an effective catalyst may be expected to vary with both the alkoxide and the hydride employed. The preferred mole ratio of up to 0.20:1 $\text{NaOCH}_3:\text{NaH}$, the upper limit being set by the tendency of increased quantities of the methoxide to decrease yields of borohydride perhaps by promoting side reactions, is therefore not necessarily the best ratio for NaOC_2H_5 employed in the same reaction. In like manner differences in preferred ranges and optimum values of cata-

lyst weight will also occur where LiH or KH is substituted for NaH, an appropriate catalyst being selected in each case.

In some of the following claims the term "catalytic amount" appears. This term does not refer to the extremely small quantities sometimes connoted by such an expression. It refers instead to quantities sufficient to promote the desired reaction and in most instances will, as exemplified, amount to an appreciable fraction of the metallic hydride employed. The term furthermore does not imply that any particular theory of the mode of action of the alkoxide is endorsed.

Having now described my invention, I claim:

1. The process of preparing an alkali metal borohydride which comprises heating the hydride of said metal with a boron halide at a temperature between about 150° and 400° C. and in the presence of an alkoxide of said metal.

2. The process of preparing an alkali metal borohydride which comprises heating the hydride of said metal with a boron halide at a temperature between about 150° and 400° C., in the presence of a catalytic amount of an alkoxide of said metal and in the substantial absence of air and moisture.

3. The method of preparing sodium borohydride which comprises heating sodium hydride with a boron halide at a temperature of about 150°-400° C. and in the presence of a catalytic amount of a sodium alkoxide.

4. The method of preparing sodium borohydride which comprises heating sodium hydride with a boron halide at a temperature of about 150°-400° C., in the substantial absence of air and moisture and in the presence of a catalytic amount of sodium alkoxide.

5. The method of claim 4 in which the boron halide is boron trifluoride.

6. The method of claim 4 in which the sodium alkoxide is sodium methoxide.

7. The method of preparing sodium borohydride which comprises heating together substantially stoichiometric amounts of sodium hydride and boron trifluoride at a temperature between about 150° and 400° C. in the substantial absence of air and moisture and in the presence of a sodium alkoxide, the mole ratio of the alkoxide to the hydride being not above about 0.20:1.

8. The method of claim 7 in which the sodium alkoxide is sodium methoxide.

9. The method of preparing sodium borohydride which comprises passing gaseous boron trifluoride over a mixture of solid sodium methoxide and sodium hydride, the mole ratio of methoxide

to hydride being not above about 0.20:1, while maintaining said mixture at a temperature between about 150° and 400° C.

10. The method of claim 9 in which the temperature is maintained within the range 250°-300° C.

11. The method of preparing sodium borohydride which comprises reacting at a temperature between about 150° and 400° C. and in the substantial absence of air and moisture, boron trifluoride with sodium hydride in the ratio of about one mole of trifluoride for each four moles of hydride, the sodium hydride being admixed with not more than about 0.2 mole sodium methoxide for each mole of the hydride present.

12. The method of claim 11 in which the sodium hydride is further admixed with a heel of product made in a previous run of boron trifluoride over sodium hydride.

13. The method of claim 12 in which the mixture of sodium hydride, heel and sodium methoxide is highly comminuted.

14. The method of claim 13 in which the comminuted mixture is agitated.

15. The method of claim 14 in which the agitated mixture is maintained at a temperature within the range 250°-300° C.

16. The method of claim 15 in which the weight of the heel present is between about 1 and 2.5 times that of the sodium hydride.

17. The method of preparing sodium borohydride which comprises passing gaseous boron trifluoride at atmospheric pressure over a highly comminuted agitated mixture of sodium hydride, sodium methoxide and a heel from a previous run of boron trifluoride over sodium hydride, the methoxide being present in the mixture to the extent of about 0.13 mole for each mole of sodium hydride and the heel being present in a weight equal to between about 1 and 2.5 times the weight of the hydride, said mixture being maintained at a temperature of 250°-300° C. in the substantial absence of moisture and air, cooling the crude reaction product and separating the borohydride from the other components of said reaction product by dissolving the borohydride in a solvent in which said other components are substantially insoluble.
